CLAIM

We claim the ornamental design for a recorder for video cameras, as shown and described.

DESCRIPTION

FIG. 1 is a front perspective view of a recorder for video cameras of the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.

The broken line showing of recorder for video cameras is included for the purpose of illustrating environment and forms no part of the claimed design. Additionally, the unevenly broken lines in the drawings define the limits of the claimed design.
